UNITED STATES PATENT OFFICE.

JOHAN HENRY EILMANN, OF MILWAUKEE, WISCONSIN, ASSIGNOR TO
JOSEPH WOLF, OF SAME PLACE.

BOX-FASTENER.

SPECIFICATION forming part of Letters Patent No. 361,149, dated April 12, 1887.

Application filed December 18, 1886. Serial No. 221,906. (No model.)

To all whom it may concern:

Be it known that I, JOHAN HENRY EILMANN, of Milwaukee, in the county of Milwaukee, and in the State of Wisconsin, have invented 5 certain new and useful Improvements in Box-Fasteners; and I do hereby declare that the following is a full, clear, and exact description thereof.

My invention relates to box-fasteners; and 10 it consists in certain peculiarities of construction and combination of parts, to be herein-after described with reference to the accompanying drawings, and subsequently claimed.

In the drawings, Figure 1 represents a perspective view of a box provided with my fastener; Fig. 2, a similar view showing a portion of a box-lid and the application of my fastener, and Fig. 3 a vertical transverse section taken through a portion of a box having my 20 fastener applied thereto.

Referring by letter to the drawings, A represents the body of a box, such as is ordinarily employed for the transportation of bottled beer, mineral waters, or other beverages, 25 and B the lid thereof.

The body A of the box is generally provided with a transverse brace-piece, C, and the lid B with transverse battens D, near its ends, that come inside against the ends and sides of 30 said box-body to prevent longitudinal and lateral play of said lid. By boring with an auger I provide the transverse brace-piece C with a seat or perforation, E, and upon the upper face of this brace-piece I secure by 35 screws F, or other suitable means, a plate, G, having a central perforation that registers with the seat or perforation in said brace-piece, but is of less diameter. Passed through the perforation in the plate G, to come within 40 the seat or perforation E in the brace-piece C, is the vertical stem H of a T-shaped latch-piece having its horizontal head I provided on the under side with downwardly-projecting lugs J. The vertical stem H of the latch-piece 45 is transversely perforated to receive a pin, K, having such a length that its ends will project from said stem, as shown in Fig. 3, and between the plate G and the pin K a spiral spring, L, is arranged on said stem of the latch-piece.

If found more desirable, a collar or suitable lugs may be employed in place of the pin K. Either of the last-named devices answer the same purpose as said pin, and in some instances it might be found preferable to cast 55 such a collar or the lugs integral with stem of the latch-piece.

A central opening, M, of suitable diameter, is made in the lid B of the box, and secured by screws or other suitable means to the under 60 side of this lid, so as to close the central opening therein, is a plate, N, provided with a slot, O, at right angles to the central brace-piece, C, of the body portion A of said box. The slot O in the plate N has a width sufficient to permit the passage of the horizontal head I of the T-shaped latch-piece, and this slot has central 65 semicircular enlargements, O', for the passage of the vertical stem of said latch-piece. At right angles to the slot O therein the top of 70 the plate N is provided at one side, near the circumference of the opening M in the box-lid B, with an eye or staple, P, that acts as a stop, and on the opposite side with a lug, Q, the latter being preferably inclined upon its 75 upper face, as best illustrated by Fig. 2.

In the operation of my invention, before the lid B is put on the body portion A of the box, the T-shaped latch-piece is turned so that its head and a portion of its stem will pass through 80 the slot O in the plate N, secured to the under side of said lid. The lid being in place, the latch-piece is turned so that its head will stand at right angles to the slot in the plate N, and the respective ends of this head come against 85 the eye or staple P and vertical face of the lug Q on said plate, as illustrated by Figs. 2 and 3. The spring L serves to keep the head of the latch-piece down tight upon the plate N on the box-lid, and thus the latter is firmly 90 fastened on the body portion of said box without the use of nails or screws.

To prevent the contents of the box from being tampered with by unauthorized parties after the lid is fastened in place, a wire or 95 strip, S, is passed through the eye or staple P on the plate N and the adjacent head I of the latch-piece, and secured by a seal, R, as shown in Fig. 2. As an additional means of sealing the box, an ordinary paper label may be em- 100

ployed to cover the central opening in the box-lid, and thus hide the fastener. To remove the lid B, the seal R is broken and the latch-piece is drawn up until the lug Q on the plate 5 N is cleared. The latch-piece is now turned to bring its head I into register with the slot O in the plate N, and the lid is free to be lifted off the body portion of the box.

In either fastening or unfastening the box 10 the operation is very simple, and the fastener has no complicated or delicate parts liable to get out of order.

Though I have described the latch-piece as being fitted in a central cross-brace of the box 15 and the plate N as centrally located on the box-lid, if found more desirable, this latch-piece may be fitted in an end or side of the body portion of said box, and the plate N correspondingly located at an end or side of the lid.

20 It is obvious that the staple or stop P and lug Q may be secured directly to the box-lid and the opening M and plate N omitted, said lid in this instance being directly provided with the slot O for the passage of the latch-piece. Such construction, though practical, is not preferable, as I desire to keep the latch-piece below the surface of the lid, so as to be 25 out of the way when the box is stored or shipped.

Having thus fully described my invention, 30 what I claim as new, and desire to secure by Letters Patent, is—

1. A box-body provided with a pivotal spring latch-piece comprising a vertical stem and a horizontal head having downwardly-projecting lugs, and the box-lid provided with a slot for the passage of the latch-head, and stops arranged in the path of said head at right angles to the slot, substantially as and for the purpose set forth.

40 2. A box-body provided with a pivotal spring latch-piece, a vertical stem, and hori-

zontal head having downwardly-projecting lugs, and the box-lid provided with a suitable opening, a slotted plate secured to the under side of said lid to cover the opening therein, 45 and the upper face of this plate provided on one side with a staple and on the other side with a lug, said staple and lug being arranged in the path of the latch-head at right angles to the plate-slot, and a suitable sealing-strip uniting the staple with the adjacent offset portion of said latch-head, substantially as set forth.

3. A box-body provided with a transverse brace-piece bored out to form a seat or perforation, a suitable plate secured to the upper 55 face of the brace-piece and provided with a perforation that registers with the bored-out portion of said brace-piece, but has a smaller diameter than the latter, a latch-piece having a vertical stem that projects into said bored-out portion of the brace-piece, and a horizontal head provided with downwardly-projecting lugs, and a spring arranged on the stem of the latch-piece to bear against the brace-piece plate, in combination with the box-lid having 60 a suitable opening, a plate secured to the under side of the lid to cover the opening therein and provided with a slot for the passage of the latch-head, a stop arranged on one side of the latter plate at right angles to the slot therein, 65 and an inclined lug similarly arranged on the opposite side of said plate, substantially as set forth.

In testimony that I claim the foregoing I have hereunto set my hand, at Milwaukee, in 75 the county of Milwaukee and State of Wisconsin, in the presence of two witnesses.

JOHAN HENRY EILMANN.
